UNITED STATES PATENT OFFICE.

REINHOLD BARTELL, OF NEWARK, NEW JERSEY.

TROUSERS PRESSER.

Application filed July 14, 1922. Serial No. 574,892.

To all whom it may concern:

Be it known that I, REINHOLD BARTELL, a citizen of the United States, residing in the city of Newark, county of Essex, and 5 State of New Jersey, have invented a new and useful Improvement in Trouser Pressers, of which the following is a specification.

In my prior patent application, Serial No. 10 507,677, filed Oct. 14, 1921, I have described certain improvements in trousers pressers, the purpose of which is to form a crease or fold in the cloth at the front and back of each leg of the garment. Means are 15 described for clamping the several plates or boards of the presser together in order to afford the creasing pressure required. My present invention relates to improvements in the clamping means, and is designed more 20 particularly to afford quick and ready means for detaching the clamping cleats and for replacing them in position. I have also shown a detachable pressure plate for connection with the lower end of the presser, 25 whereby, the lower ends of the trousers legs may be properly creased and pressed.

In the drawings, I have shown several slight modifications in the means for attaching and securing the clamps in place, all 30 of which are deemed to come within the general scope of the invention.

In the drawings:

Fig. 1 illustrates a plan view of the presser with the clamps in adjusted position.

Fig. 2 is a rear plan view of the same.

Fig. 3 is an edge elevation.

Fig. 4 is an end elevation of the same.

Fig. 5 is a cross-section of the presser plates showing the means by which the edges of the plates are connected together.

Fig. 6 is a similar section, showing a slight modification of the means for connecting the edges of the plates together.

Fig. 7 is a fractional plan view of one 45 of the cleats and its keeper showing the means by which the width of the presser may be adjusted.

Fig. 8 is a fractional plan view of one 50 of the keepers, showing the adjusting slots in the end thereof as located closer together in order to provide for a larger number of adjustments.

Fig. 9 is a plan view of a modified form 55 of the adjustable fastening for the rear plates.

Fig. 10 is a side elevation of the same.

Fig. 11 is a modification of the front fastening cleat and its keepers.

Fig. 12 is a plan view of a separable extension for insertion beneath the garment 60 and between the upper and lower plates for creasing the lower ends of the trousers legs.

Fig. 13 is an edge view of the same showing the method of folding such extension over to fasten it to the body of the plate 65 with the trousers leg therebetween.

Figs. 14 and 15 illustrate forms of extension flaps to be fastened to the bottom plates 3 and 4 with the lower ends of the trousers leg folded back upon said plates 70 with the extension flaps to be folded over and fastened above them.

Similar reference numerals refer to like parts throughout the specification and drawing.

The presser consists primarily of the upper plates 1, 2 the lower plates 3, 4. The outer edges of the plates 1 and 4 are connected together by a strip of fabric 5, the edges of which are laid upon the outer 80 edges of the boards and lines of stitching 6, 7, 8 and 9 are run along the edges of the boards to secure such strip of fabric in place as shown in Fig. 5. The strip of fabric is of a width sufficient to permit the 85 folding over of the two plates so as to afford the narrow space 10 between them as shown in Fig. 5. The inner edges of the bottom plates, 3 and 4 are connected together by a strip of fabric 11 with the 90 ends 12, 13 folded under and secured by lines of stitching 15, 16. If desired, a central fold 17 may be provided longitudinally of the strip 11, the limbs of such fold being held together by a line of stitching 95 at their base. This affords a means for enlarging or separating the plates when desired, to fit a larger garment. This may be readily done by ripping out the stitching at the base of the fold.

In practise the plates 1, 2, 3 and 4 are made of what is known in the art as Upson board, which is very similar to heavy straw board but is water proof and somewhat stiffer than the usual straw board of the 105 same weight and thickness. Upon the face of each of the plates 1, 2, 3 and 4 are the longitudinal strips 18, 19, 20 and 21. These may be of wood or metal as desired. When made of wood, as shown, they are secured 110

to the faces of the plates by gluing or, if desired, may be secured by rivets. The ends of each of strips 18, 19, 20 and 21 are provided with the flat metal keepers 22, 23, 24, 25, 26, 27, 28 and 29, riveted in place as shown. The ends of the keepers are provided with the open slots 30, spaced apart as shown. It will be noted, however, that the slots upon one pair of the keepers are spaced closer together than those upon the other pair of keepers upon the same side of the presser. Beneath the keepers, as above described, the several cleats, 31, 32, 33 and 34 are inserted, said cleats spanning across the upper and lower ends of the presser plates. In order to retain these cleats in place, they are connectd together in pairs by means of the tapes or strips of webbing 35, 36, a section of each of which, as 37, 38 may be made of elastic so that when one of the cleats is fitted under its keepers the other, being connected by means of the tape 35 or 36, may be stretched down and slipped under the other pair of keepers. Each of the cleats is provided with a pair of pins 39 for insertion in any of the slots 30 in the keepers, so that the plates 1 and 2, 3 and 4 may be adjusted toward or away from each other to fit the various sizes of garments to be pressed.

In practise, the presser plates are laid out upon a flat surface with the plates 3 and 4 uppermost, and the cleats 33, 34 are adjusted under their respective keepers. The plates are then turned over with the sections 1 and 2 uppermost and they are folded out flat while the garment is laid upon and shaped upon the upper faces of the two boards 3 and 4, after which, the two boards 1 and 2 are carefully folded over the edges of the garment and the cleats 31, 32 are adjusted as shown in Fig. 1.

It will be noted that the longitudinal strips 20 and 21, with their keepers 26, 27, 28 are located upon the plates 3 and 4, in a position to leave a considerable space between the edge of the cleat 34 and the lower end of the presser. This is to afford a space for permitting the lower ends of the trousers to be folded back over the rear plates 3 and 4 and there held in place by the means hereinafter described.

In Fig. 6, I have shown a slightly different form for fastening the several plates together. In this case, the two plates 1 and 4, and the plates 2 and 3 are laid flat upon a surface with their edges close together. Upon their line of juncture I place strips of oilcloth as 40, 41 with the face thereof covered with some good water-proof adhesive, so as to thoroughly cement said strips to the edges of the several boards. If desired, lines of stitching as 42 may be run along the edges of the board and the edges 65 of the strip as shown in Fig. 6. A wide

strip of the oilcloth 11 may be placed on the lower side of the two plates 3 and 4 and secured thereto by cementing as above described in order that the two sets of boards, 1, 4 and 2, 3 may be secured together. The same style of cleats and fastening devices as shown in Figs. 1 to 4 may be used in connection with this modification. The use of the strips of oilcloth for connecting the edges of the boards together as described in connection with Fig. 6 is advantageous in this respect; when pressing trousers better results are obtained by dampening the line of the crease, and it will be observed that the line of the crease will be located between the folded parts of the oilcloth strips 40, 41; the moisture thus applied, will not penetrate the oilcloth and even though the plates 1, 2, 3 and 4 are made of non-water proof material, the moisture cannot in any way affect them.

As above described the slotted ends of the keepers 22 to 29 inclusive, in conjunction with the several pins 39, afford a convenient and ready means for adjusting the plate to fit different sizes of garments, so that the creased edges of the same may be in as close proximity to the outer edges of the plates as possible, for at those points the greatest pressure is exerted when the plates are clamped together.

In some cases I may use a single fastening cleat upon the two bottom boards, 3, 4 as shown in Fig. 9. The cleat 50 is pivoted by means of the rivet 51 to the plate 3 near its inner edge as shown, with one end swinging under the keeper 52 and the other end extending across and overlapping the plate 4, so as to swing beneath the keeper 53. Upon the keeper 53 is a spring member 54 having a pin 55 at its forward end so that it may be set into any one of a series of apertures 56 in the adjacent end of the cleat 50. In this manner the plates 3 and 4 may be adjusted towards and away from each other and firmly secured.

In Fig. 11, I have shown a slightly modified form of adjusting means. In this case the cleat 57 is provided with a series of notches 58, 59 into any one of which the indentations 60, 61 on the keepers 62, 63 may be inserted. Other forms of adjustment may be used if desired or preferred. I have shown several different modifications, the purpose of each of which is to afford a secure fastening means by which the plates may be held in their adjusted positions.

In Fig. 12, I have shown a separable extension 64, which has a triangular piece 65 integral therewith for insertion between the upper and lower plates, and having lateral flaps, 66 and 67 to fold over the exposed ends of the trousers legs and thereafter the extension is folded over upon the plates 3, 4 with the tongue 68 tucked beneath the ad-

jaçent cleat 34. If desired a strong rubber band may be slipped over this folded extension to hold it in place.

In Fig. 14, I have shown the extensions 5 69 and 70 as being attached to extensions 6' of the fabric strips 5', shown in Fig. 1, such fabric strips extending beyond the extension 69, 70 with their ends tied together as means by which the presser with its contents 10 may be suspended from a hook or used to wrap around the extensions 69, 70 after the same have been folded over against the plates 3, 4.

In Fig. 15, I have shown lateral flaps 71, 15 72 as secured along the lower ends of the two plates 3, 4 by means of the fabric strips 73, 74 so that said flaps 71, 72 may be folded over the lower extremities of the trousers after they have been turned up and placed 20 upon the two plates 3, 4. Fastening strings or tapes 75 may be attached to the free edges of the flaps 71, 72 to be tied together after said flaps have been folded over so as to hold the trousers in place.

25 From the foregoing description, it will be seen that I have provided a presser which in general contour conforms to the shape of the garment to be pressed and that the several devices illustrated and described firmly unite 30 the parts together when the garment is in place and confines the edges of the garment between the upper and lower plates with considerable pressure. The provision of the extensions illustrated in Figs. 12 to 15 inclusive, also affords effective means for extending the crease at the front and rear of the trousers legs, the entire length thereof.

While I have described the plates 1, 2, 3 and 4 as made of Upson board, yet I do not 40 desire to confine myself to that material alone, since wooden plates or plates made of straw board may be used and serve the purpose under certain conditions, fully as well. The Upson board is preferred because of its 45 extreme lightness, its great toughness and its water-proof qualities, although slightly more expensive than either straw board or wood.

I claim:

50 1. In a trousers presser, the combination of a pair of lower plates, means for securing said plates in relative spaced relation to each other, comprising a strip of fabric secured to the adjacent edges of said plates, a pair of upper plates of similar shape, strips of fabric connecting the upper and lower plates in pairs, keepers upon each of said plates and cleats for insertion beneath said keepers to clamp said plates together.

55 2. In a trousers presser, the combination of tapering upper plates and a similar pair of lower plates, a strip of fabric, connecting the adjacent edges of said lower plates together in spaced relation to each other, strips of fabric, connecting the non-ad-

jaçent edges of said lower plates with the corresponding edges of said upper plates, clamping means upon said lower plates, said clamping means having devices connected thereto for holding said lower plates in fixed relation, and clamping means upon the upper plates for securing the same in fixed relation to said lower plates.

3. In a trousers presser, the combination 75 of a pair of upper plates, and a pair of lower plates, means for flexibly connecting each of said upper plates with the corresponding lower plates and means for flexibly connecting said lower plates together to form a longitudinal channel therebetween, keepers upon said lower plates and a cleat adapted to be inserted beneath said keepers and having means thereon to hold said lower plates in fixed spaced relation, keepers upon the upper plates and cleats adapted to be 80 inserted beneath said keepers, to hold said upper plates in fixed spaced relation.

4. In a trousers presser, the combination 90 of a pair of lower plates, means for securing said plates in relative spaced relation to each other, comprising a strip of fabric secured to the adjacent edges of said plates, and a pair of upper plates of similar shape, strips of fabric connecting the upper and lower plates in pairs, keepers upon each of said plates, cleats for insertion beneath said keepers to clamp said plates together, and a separable extension, adapted to be inserted between said upper and lower plates, said extension having lateral flaps adapted to fold over the extremities of the garment and thereafter said extension and said garment folded over and secured to the ends of said plates.

5. In a trousers presser, the combination 105 of tapering upper plates and a similar pair of lower plates, a strip of fabric, connecting the adjacent edges of said lower plates together in spaced relation to each other, strips of fabric, connecting the non-adjacent edges of said lower plates with the corresponding edges of said upper plates, clamping means upon said lower plates, said clamping means having devices connected thereto for holding said lower plates in fixed spaced relation, clamping means upon the upper plates for securing the same in fixed relation to said lower plates, and a separable extension, adapted to be inserted between said upper and lower plates, said extension having lateral flaps adapted to fold over the extremities of the garment and thereafter said extension and said garment folded over and secured to the ends of said plates.

6. In a trousers presser, the combination 115 of a pair of lower plates, means for securing said plates in fixed relation and spaced apart from each other, said means comprising a keeper upon each of said plates, and 120

a cleat adapted to be fitted in adjustable positions with respect to said keeper, said cleat and keeper having means thereon for holding said plates in fixed spaced relation to each other, and extensions adapted to be connected to the ends of said plates and folded over thereupon to enclose the extremities of a garment therebetween.

7. In a trousers presser, the combination of a pair of upper plates, and a pair of lower plates, means for flexibly connecting each of said upper plates with the corresponding lower plates and means for flexibly connecting said lower plates together

15 to form a longitudinal channel therebetween, keepers upon said lower plates and a cleat adapted to be inserted beneath said keepers and having means thereon to hold said lower plates in fixed spaced relation, keepers upon the upper plates, cleats adapted to be inserted beneath said keepers to hold said upper plates in fixed spaced relation, and extensions adapted to be connected to the ends of said plates and folded over thereupon to enclose the extremities of a garment there- 25 between.

REINHOLD BARTELL.
